UNITED STATES PATENT OFFICE.

HENRY E. REEVE, OF BROOKLYN, NEW YORK, ASSIGNOR TO AUTOMATIC FIRE ALARM COMPANY, OF NEW YORK, N. Y., A CORPORATION OF NEW YORK.

ELECTRIC ATTACHMENT FOR TANKS.

No. 851,775.

Specification of Letters Patent.

Patented April 30, 1907.

Application filed February 8, 1906. Serial No. 299,297.

To all whom it may concern:

Be it known that I, HENRY E. REEVE, a citizen of the United States, residing at Brooklyn, county of Kings, State of New York, have invented certain new and useful Improvements in Electric Attachments for Tanks, of which the following is a full, clear, and exact description.

My invention relates to electric attachments for tanks.

It is customary in systems for water supply and fire protection to locate a tank containing water upon the roof of the building or at a high elevation. It is essential that this tank be kept filled with water. This is sometimes taken care of automatically, and sometimes by giving a warning or alarm to the person in charge of the pumping apparatus.

It is the object of my invention to provide mechanism for supervising the tank, which mechanism shall be simple and reliable in character, and not subject to interference with its operation caused by oxidation, rusting, or incrustation of its working parts.

In the preferred form of the invention, as illustrated in the accompanying single sheet of drawings, the invention consists in the mounting of the operating parts of the float operated switch in a reservoir containing oil, the parts of the mechanism above the surface of the oil being inclosed by a bell. In this manner, the parts are continually kept in a properly lubricated condition, and oxidation prevented.

Figure 1 is a plan view of a float operated switch, the sealing bell being shown in section, and also showing a diagram of a circuit for automatically starting a motor which may control a pump, as is customary in devices of this character. Fig. 2 is a side view and partial section of the apparatus more particularly involving my invention. Fig. 3 is a sectional view at right angles to that shown in Fig. 2, the float arms being removed.

1 indicates the wall of the tank which contains water for supplying the service, and which tank will be provided with a suitable

inlet and a suitable outlet as is customary.

2 is a receptacle, preferably secured to the interior wall of the tank, and containing the parts of the switch mechanism and also adapted to contain a substantial body of oil.

3 indicates a float, which is sustained at the surface of the water in the tank and rises and falls according as the water level changes.

4 is a shaft rotatably mounted in the receptacle, and preferably having two upright tubular posts 5-5 connected by the tubular arms 6-6 to the tubular float bar 7.

8 indicates a thermostatic device which may be employed in connection with the float for indicating the changes of temperature in the tank. The wires from the thermostat may pass through the tubular members and through the shaft 4 into the receptacle and then be led outward in any suitable manner. Since the thermostatic device is not involved in this particular invention, details of construction and circuits therefor are omitted.

It is obvious that the float might be sustained by a single arm instead of two arms, as 6-6, but the parts are better balanced by the construction shown.

9 is a base member for the switch preferably formed of slate and supported in the receptacle 2 in any suitable manner.

10 and 11 are the terminals of an electric circuit. 10' and 11' indicate another pair of terminals.

12 is a support carried by the base 9 which in turn pivotally supports the two-armed lever. 13 is one arm of this lever, which acts as a switch arm to connect the terminals 10 and 11 when in the position shown. The other arm 14 of the lever is connected to the rocker arm 15 by means of the spring 16. This rocker arm 15 oscillates with the shaft 4 as the float rises and falls. In the position shown, the float is at its high water point. When the water level falls the float falls, the rocker arm 15 oscillates toward the right, and the spring 16 exercises its pressure on the end of the arm 14 to the right of the axis of the two-armed lever, and throws the lever so as to move the arm 13 down and engage the two switch contacts 10' and 11'. The operation, of course, is reversed, and the parts thrown into the position shown in Fig. 2 when the water level is restored to its normal condition.

17 is a bell-like device or cover which is adapted to fit over the moving parts of the switch, the receptacle 2 being partially filled with oil, for instance, to the level of the dot and dash line shown in Figs. 2 and 3. The

bell 17 is placed over the parts in inverted position with the lower edge of the bell resting on the bottom of the receptacle below the surface of the oil. This secures the parts

5 from all forms of chemical action which might interfere with the condition of the contacts, moving parts, etc.

An electric circuit is connected to the switch terminals, either for automatically

10 giving an alarm or controlling a pumping apparatus when the water level reaches a predetermined point or points. The electric circuit may be connected as by the wires 18 and

15 19 led out through the pipe 20 to a motor 21, for automatically supplying power to operate the pumps when the water level reaches its

minimum, and shutting off power when the predetermined water level is restored.

It is obvious that provision may be made 20 for locking the bell in place or for automatically giving an alarm in case the bell is tampered with.

The advantages of the simple method of construction of the float operated switch and

25 the method of protection thereof will be apparent to those acquainted with the problems of supplying water from tank systems.

What I claim is:

1. An attachment for tanks comprising a 30 receptacle, a switch mounted therein, an actuating float, a pivot shaft therefor in said receptacle, operative means of connection between said shaft and said switch, a substantial body of oil immersing said pivot shaft, and a sealing bell inclosing the parts of the switch.

2. A tank attachment comprising a receptacle for containing a substantial body of oil, a float having a pivot shaft mounted in 35 said receptacle and immersed in the oil there-

in, an electric switch operative means of connection between said switch and said float shaft, and a sealing bell inverted over said switch.

3. An attachment for tanks comprising an oil holding receptacle, a float, a pivot shaft therefor immersed within the oil in said receptacle, a switch in said receptacle, controlled by the movement of said float, and a bell for sealing said switch. 45

4. A tank attachment comprising an oil holding receptacle, a float, a pivot shaft therefor mounted in said receptacle, a pair of arms connecting said shaft and float, a switch, and a bell inclosing said switch, having its lower edges immersed in the oil in said receptacle. 50

5. A tank attachment comprising an oil holding receptacle, a pivot shaft therefor, a float connected to said shaft, a rocker arm 60 moving with said shaft, a switch, a spring connecting said switch with said rocker arm, and a bell for sealing said switch.

6. A tank attachment comprising a receptacle for holding a sealing fluid, a switch 65 mounted therein, a bell inclosing said switch, a float and operative means of connection between said float and said switch.

7. A tank attachment comprising a receptacle for holding a sealing fluid, a switch 70 mounted therein, a bell inclosing said switch, a pivot shaft in said receptacle, operative means of connection between said shaft and said switch, a float and a lever arm connection between said float and said shaft.

HENRY E. REEVE.
